UNITED STATES PATENT OFFICE.

JAMES L. MITCHELL, OF SANTA PAULA, CALIFORNIA.

AUTOMATIC CIRCUIT-BREAKER.

1,104,439.

Specification of Letters Patent. Patented July 21, 1914.

Application filed November 14, 1912. Serial No. 731,448.

To all whom it may concern:

Be it known that I, JAMES L. MITCHELL, a citizen of the United States, residing at Santa Paula, in the county of Ventura and State of California, have invented certain new and useful Improvements in Automatic Circuit-Breakers; and I do declare the following to be a full, clear, and exact description of the invention, such as will enable others skilled in the art to which it appertains to make and use the same.

This invention is an electrical circuit breaker, and its object is to so modify the construction of an ordinary knife switch or circuit closer that the same shall be thrown open and the circuit broken in the event that the current becomes suddenly either excessive or extremely weak, by reason of an overload or an underload, or in the event 20 that the circuit is entirely broken at some point.

The invention consists in the specific construction of the circuit breaker whereby this general idea is carried out, all as hereinafter more fully described and claimed, and as shown in the drawings wherein—

Figure 1 is a front elevation and Fig. 2 a side elevation of this device complete. Fig. 3 is a plan view thereof. Fig. 4 is a detail 30 in side elevation showing the trigger as tripped, and Fig. 5 is an enlarged perspective detail of the trigger alone. Fig. 6 is a perspective detail of the main trip lever, and Fig. 7 a similar detail of the secondary 35 trip lever.

In the drawings I have shown my invention as applied to an ordinary three-blade knife switch whose blades B are pivoted at P to a support S and passed between spring 40 terminals to make the circuit complete at the points T when the switch stands upright, and the upper ends of said blades are connected by an insulated bar I carrying a handle H.

No claim for novelty is laid on this switch or circuit closer, as it is the ordinary type now in common use, and it is obvious that my invention could be applied to switches of this character having a greater or lesser 50 number of blades, or to other types of switches without departing from the principle involved.

Coming now to the details of the present invention, the support S carries a horizontal 55 framework 1 suitably braced as at 2 and pierced with an opening 3 through which

passes an arcuate rod 4 which is secured at its upper end as at 5 to the handle H and is headed at its lower end as at 6, and between said head and the lower side of the framework 1 an expansive spring 7 is coiled on said rod so that its tendency is to draw the same downward through the opening 3 and to throw the switch open. However, any other suitable mechanism might be employed for holding the switch normally open, and the illustration of this form must therefore be taken as typical only. At a suitable point said rod is provided with a notch 8, so disposed that it stands just above 70 the framework 1 when the switch is closed as seen in Fig. 1.

In Fig. 5 is best shown the form of trigger which I preferably employ in this device. The same comprises a block-shaped body 10 having a nose 11 at its front end adapted to engage said notch 8, and it is important that the nose project to one side from the upper corner of the block, while the rear lower corner of said block is provided with a notch 12 adapted to be engaged by the tripping mechanism hereinafter described. The trigger is also provided with a handle 13 by means of which it may be set. This trigger is pivoted at 14 within a suitable bearing 15 mounted on the frame, 80 1 and at such point (see Fig. 4) that the descent of the rod 4 under the impulse of the spring 7 will carry the notch 8 downward and with it the tip of the nose 11 so 85 that the trigger turns on its pivot 14 if it be free. On the other hand, if some mechanism engages the notch 12 at the rear of the body 10, the nose cannot descend and therefore the rod 4 will be held elevated against 90 the tendency of its spring 7. Coacting with said trigger is a tripping mechanism consisting of a trip lever 20 whose nose or front end 21 is adapted to engage or to be engaged with said notch 12 when the nose 11 100 of the trigger is raised. To this end the lever 20 is pivoted at 24 at a suitable point, preferably within the same bearing 15 which carries the trigger; and these elements are shown engaged in Fig. 1 and disengaged in 105 Fig. 4. The rear end of the trip lever is longer and heavier than its front end or nose 21, and is slotted as at 22, this end 23 preferably overlying the frame as best seen in Fig. 3. Supported by said frame is a 110 solenoid 25 whose floating core 26 carries an upright pin 27 which rises through the

frame and projects through said slot 22, and on said pin beneath the rear end 23 of the lever 20 is fixed a collar 28 or similar device so that when this solenoid is energized and its core rises, the pin will rise and the collar 28 thereof will lift the rear end of the lever 20. The obvious result of this action is that the nose 21 disengages the notch 12 in the trigger, and the latter may fall to the position shown in Fig. 4 so that the rod 4 can descend, and the switch is thrown open under the expansive influence of the spring 7.

The tripping mechanism for the trigger 15 also by preference includes a second trip lever 30 whose nose 31 is its longer and heavier end and stands beneath the slotted rear end 23 of the main trip lever 20. This second or supplemental trip lever is pivoted at 34 in a suitable bearing 15' carried by the frame 1, and its rear end 33 is slotted as at 32. Carried by said frame is a coil 35 whose core 36 is by preference rather heavy, and this coil rises through the frame and 20 extends loosely through the slot 32, above which it is provided with a collar or similar device 38. By preference the secondary lever 30 is disposed at right angles to the main lever 20 as best seen in Fig. 3, although 25 this is a detail of construction dependent upon the shape of parts.

The action of this device will now be clear when it is understood that both coils 25 and 35 are included in the circuit which passes 30 through the switch, although the wiring is not shown in the drawings. When the switch is closed and the parts stand at rest, they remain in the position shown in Figs. 1, 2 and 3 as long as the current is flowing 35 and is normal. If now a sudden overload is thrown onto the circuit for any reason, the core 26 within the solenoid 25 rises, the collar 28 lifts the rear end 23 of the main lever 20, and its front end or nose 21 is 40 borne downward out of engagement with the notch 12 of the trigger as seen in Fig. 4, so that said trigger drops and disengages the notch 8 of the rod 4 and the spring 7 expands and throws the switch open. There 45 is no provision for permitting the switch to remain closed, even though it is set by hand, so long as the overload continues in circuit; but when the conditions are restored to normal, the switch can be closed by raising its 50 handle H which brings its notch 8 into position to be reengaged by the nose 11 of the trigger, the latter being actuated by its handle 13 and the nose 21 of the lever 20 being reengaged with the notch 12. With the 55 conditions at normal, if the circuit should be broken from any cause the heavy core 36 in the coil 35 will fall and its collar 38 will bear downward on the rear end 33 of the secondary lever 30, with the result that the 60 nose 31 of the latter will rise. As said nose

underlies the rear end 23 of the main lever 20, the latter will move and the action above described will be repeated. To be more exact, whenever the voltage in the circuit falls to such a point that it no longer sustains 70 the rather heavy core 36, the secondary trip lever 30 is moved; this moves the primary trip lever 20, and this in turn trips the trigger. On the other hand, whenever the current in the circuit is increased to such an 75 extent that the core 26 in the solenoid 25 is caused to rise, its collar 28 actuates the main lever 20 with the result desired, but in moving it does not move the secondary lever 30. So that it will be seen that the action of the 80 two coils or solenoids is independent, while producing the unitary result. I might say that while I have shown a solenoid and core, it is possible to use electro-magnets at these 85 points and substitute armatures for the levers shown, so long as the armatures are themselves mounted on levers which produce the result of disengaging the heel of the trigger and permitting its nose to fall and release the notch 8. These suggestions 90 are not illustrated, because the modifications of which the device is susceptible will be clear to any electrician. The materials and proportions of parts are not essential to the 95 successful operation of the whole.

What is claimed as new is:

1. The combination with a frame having an opening, a notched rod projecting through the opening and headed, and a spring coiled thereon between said head and frame; of a trigger movably mounted on said frame with its nose adapted to engage said notch and its heel provided with a notch, a pivoted lever whose nose is adapted to engage the notch in said heel when the trigger is set, and a coil whose core is connected with the lever and moves the latter to disengage the trigger when the coil is energized.

2. The combination with a notched rod, and means tending to move it longitudinally; of a pivoted trigger having its nose adapted to engage said notch and its heel provided with a notch, and tripping mechanism including a lever whose nose is adapted to engage the notch in said heel when the trigger is set, a pivot for said lever, an upright coil, and a core therein carrying a collar contacting with the rear arm of said lever and adapted to actuate the latter to disengage said trigger when the coil is energized.

3. The combination with a switching mechanism normally held under tension and including a rod; of a frame having a hole through which said rod moves when the switch is thrown; a trigger pivoted on the frame and having a nose adapted to engage said rod when the switch is closed, a handle on said trigger, a trip for holding said trigger with its nose in engaging position, and

a coil for causing said trip to release said trigger when the conditions in the circuit being controlled become abnormal.

4. The combination with a switch normally held under tension, and a rod carried by its handle; of a frame through which the rod moves when the switch is thrown, a trigger consisting of a block-shaped body pivotally mounted in a bearing upon said frame 10 and having a nose projecting forward from one upper corner and adapted to engage said rod, the body also having a notch in its rear lower corner, and tripping mechanism for holding said trigger with its nose in engaging position.

5. The combination with a switch, a frame having an opening, and a rod projecting from the switch through said opening and having a notch; of a movable trigger whose 20 nose is adapted to engage said notch and whose heel is notched, a pivotal support for this trigger on said frame, a trip lever pivoted between its extremities on said frame with its nose adapted to engage the notch in 25 the heel of the trigger when the latter is set, and electrically-actuated mechanism for moving the rear arm of said trip lever when the conditions in the circuit being controlled become abnormal.

30 6. The combination with a switch, a frame having an opening, and a rod projecting from the switch through said opening and having a notch; of a trigger pivoted on said frame with its nose adapted to engage said 35 notch, a lever pivoted between its extremities on said frame with its nose engaging said trigger to hold it set, the rear arm of said lever being slotted, a solenoid carried by said frame and in circuit with the circuit 40 being controlled, a floating core within said solenoid, a pin rising therefrom and projecting loosely through the frame and the notch in the rear arm of the lever, and a collar fast on said pin beneath said arm, for 45 the purpose set forth.

7. The combination with a frame, and a trigger pivoted on said frame; of a lever pivoted on said frame with its forward arm engaging said trigger when the same is set, a second lever pivoted on said frame with its 50 forward arm engaging the rearward arm of said first lever, an over-load coil controlling the rear arm of said first lever, and an under-load coil controlling the rear arm of said last lever.

55 8. The combination with a frame, and a trigger thereon; of a lever pivoted on said frame with its forward arm engaging said trigger when the same stands set, a second lever pivoted on said frame with its forward 60 arm beneath the rearward arm of said first lever, an over-load coil carried by the frame beneath the rear arm of said first lever, connections between such arm and the core of this coil, an under-load coil carried by said 65 frame beneath said second lever, and connections between the latter and the core of this coil, for the purpose set forth.

9. The combination with a trigger; of a pivoted lever with its forward arm engaging 70 said trigger and its rearward arm slotted, a second pivoted lever with its forward arm engaging beneath the slotted arm of the first lever and its rear arm slotted, a solenoid having a floating core, a pin rising 75 therefrom through the slotted rear arm of the first lever, a collar on this pin beneath said arm, a coil beneath the rear arm of the second lever, a weighted core therein rising through the slot of such lever, and a collar 80 on the core above said arm, for the purpose set forth.

In testimony whereof I have hereunto set my hand in presence of two subscribing witnesses.
